Short & Bradford.

Diving Armor.

Patented Feb. 18, 1830.

Small Short and Hand Pressed Case of Ammable Maps
S. & N. S. Patented.

The Machine referred to in these Letters Patent and making part of the same containing a description of the works of the said small Short and Noah Bradford, inventors of this improvement the machine for exploring water, &c. denominated the Submarine Explorer.

To all to whom these presents shall come,

Be it known that Michael Short and Noah Bradford both of Barnstable in the County of Barnstable and Commonwealth of Massachusetts have invented a new and useful machine or apparatus for the purpose of exploring sea water, looking under water and viewing properly lost mines which they have denominated the Submarine Explorer. That the following is a full and exact description of the construction and operation of the said machine or apparatus as invented by us. No. 1. A Seat or Buoy (at in the drawing here to onward) is constructed of Cork or such other materials) in the form of an inverted Bell though left flaring. of sufficient dimensions to support the machine and hold the necessary number of men to work it. say five feet diameter at top and three feet diameter at the bottom of five feet in height and covered with leather or other materials) which shall render it impervious to water and also bind with it. To the bottom of this (at B) is attached by screws or rivets) a tube or hose (B.B.) constructed of leather or other ammable materials, made watertight and of sufficient thickness to resist the pressure of the water diminishing in size downward from two to five feet when it is reduced to two feet diameter and of this size continues till within the height of a man's shoulder of the lower end (Y.) when two branches (C.F.) resembling somewhat the arms of a garment, and fitted to receive a man's arms are attached to it by screws or rivets. said hose continuing the same size or nearly the same size to within about three feet of the bottom (B) when it is divided into two parts fitted to receive a man's legs & feet (C.C.) the seams of this hose are secured by screws, rivets and the hose is kept extended by means of iron hoops, on the inside secured to the covering by screws (or rivets) and increasing downwards in strength and frequency in proportion to the increased pressure of the water. On the arms and legs the hoops (if hoops are used) are kept in place by iron splinters fastened to each by screws or rivets, in which splinter a joint is made at the elbow and knee

58

To facilitate the motion of the body in walking and working, additional to the spring of the arm, the monitor has two spiral wires made of hoops, and it hangs them proportionable as they admit of great freedom and variety of motion, and further it may be found most convenient for the legs also. The machine is sunk by means of weights (A. B. C.) suspended by a chain from hooks (D. E.) secured into a hoop and furnished with a screw to prevent the chain from being easily disengaged. And, it may be necessary or convenient to suspend weights from each of the hooks owing to the weight or force of the hoop, inside and outside being thrown each hoop outside and, perhaps, the same inside. To prevent being elevated and depressed by the undulations of the water the hoop is contracted by folds, for the distance of four feet from the Buoy, so that the Buoy may rise with any ordinary wave without effacing the lower part of the apparatus, and to continue its position when the wave subsides, these spiral wires (like G. I.) of sufficient strength to effect this object without moving the machine one placed on the outside and secured to the hoops by screws, so as to extend the distance of six feet downward. To prevent the hoop from being extended in any particular part, chains are extended from top to bottom and attached to the said hooks or rings, and made to bear equally on all the hoops, as they pass the spiral wires from which they pass. They are so slackened as not to take effect till the hoop becomes extended when they do, and prevent a strain of the hoop. About two third of the distance from the top to the bottom of the Buoy, there is a platform which is intended to be represented by the figure D. exhibiting a section of the Buoy, having in its concentric aperture (D.) of the diameter of two feet around which is an iron railing on the top of which is a windlass (I.) on this platform the man who and the operator stand. Thro this aperture the operator descends by stepping on the hoops and carries with him fastened round his body a rope from the windlass and swings himself in the parts of the bottom adapted to his body and limbs. The windlass and ropes facilitate and hasten his ascent in case of sickness, coincident. To enable him to see external objects through glass of thick glass (as H.) cut out in one in front and one on each side and set in iron bars, or copper frames and secured to the hoop by screws or rivets. To enable him to use his hands with ease a pair of leather gloves or mittens are fitted by screws or rivets to the middle of the iron bars of the arms and the fingers of the mittens may check circulation and occasion cold, it will be necessary to withdraw them, and to prevent the pressure of the mittens from hurting

357

with the gloved or mittened hand (continued) traps cap (P & C) are made to come on the
 iron cuffs, and suspended by chain from hookings on the traps, with the hand
 (C.) he draws the cap (C.) on the arm & then with the remaining hand takes the
 cap P by a small pinto or handle fixed to the inside, and draws it after his hand
 and so out it inside. A ring of India rubber is well bound about to aid in
 resisting the pressure of the water, when the hand is in the glove. In case fresh
 air is required it is supplied by a tube extending from the Buoy to the breast of
 the operator inside, and inflated by a bellows (A) (or an air pump). To keep
 the apparatus in a perpendicular position when placed in the tide or current
 naps; rigging ropes (R. R. &c.) are fastened to several of the hooks, or rings in the
 stocks, uniting at a proper distance (X) and extending to a vessel or other object
 to which it is secured (if necessary avoiding the seams) they are made
 with oblong heads, are inch in length and placed contiguous to each other.
 On these inside, circular nuts, one inch in diameter are secured which con-
 sequently meet each other and make it perfectly tight. On the upper part how-
 ever where the spiral wires, are placed to facilitate the folding the heads and nuts
 of the screws are made smaller. An idea of the screw may be obtained from the fig-
 ure W. The drawing which accompanies this represents an apparatus about eight-
 teen feet long, but the length may be greater or less, according to the depth
 of the water in which it is intended to work. To enable him to descend to a
 greater depth, there is a screw from the Buoy. In case of any slight leak-
 age thro' the apparatus by which the situation of the operator is rendered
 wet and uncomfortable, the water is taken out by a small hydraulic ex-
 cline in the Buoy. To enable him to descend to a greater depth the appa-
 ratus is unscrewed from the Buoy and also from the lower part, just above
 the head, (at J.J.) and to protect him from the water a cast iron (cuff)
 cap (T.) is screwed on in its place at J. To supply him with air a small
 tube connected with an air pump in the Buoy passes into the apparatus
 just below the operators head. another similar tube passing thro' said cap and
 screwed into it extends to the Buoy whereby a stop cock the impure air is
 let off as much as requires. To enable him to change position, hooks are
 attached to the several traps, from any of which he may suspend the weight
 and then form any attitude he may wish to assume. To raise him to the sur-

few when required, ropes are fastened to as many of the hooks as necessary, uniting
over his head and attaching the windlass in the Buoy. What we claim
as new and for which we ask an exclusive right, is the formation of a floating
Raft or Buoy in the form of an inverted Bell or in any other convenient
shape and the attaching thereto a tube of leather or other material made im-
permeable to water and extending from the surface to the bottom of the water
and of sufficient dimensions for a person to ascend and descend and the
furnishing said tube at bottom with the kind of stop or covering above de-
scribed, so that the whole shall form a watertight case in which
respect, it differs from all other diving apparatus before known.

At Wimpey whereof we have hereunto set our hands and seals this twenty-
third day of January AD Eighteen Hundred and Thirty
